(57) **CLAIM**

The ornamental design for a MOLD FOR MULTI-CHAMBER POD, as shown and described.

DESCRIPTION

FIG. 1 is a front perspective view of the MOLD FOR MULTI-CHAMBER POD;

FIG. 2 is a top view of the MOLD FOR MULTI-CHAMBER POD;

FIG. 3 is a bottom view of the MOLD FOR MULTI-CHAMBER POD;

FIG. 4 is a front view of the MOLD FOR MULTI-CHAMBER POD;

FIG. 5 is a rear view of the MOLD FOR MULTI-CHAMBER POD;

FIG. 6 is a left side view of the MOLD FOR MULTI-CHAMBER POD,

FIG. 7 is a right side view of the MOLD FOR MULTI-CHAMBER POD; and

FIG. 8 is a cross sectional view along lines 8-8 of FIG. 2 of the MOLD FOR MULTICHAMBER POD.

The broken lines showing of items in the figures depict portions of the article that form no part of the claimed design.

1 Claim, 4 Drawing Sheets
